CLAIM

What is claimed is the ornamental design for a guitar controller, as shown and described.

DESCRIPTION

FIG. 1 is a front perspective view of the guitar controller; FIG. 2 is a front view of the guitar controller; FIG. 3 is back view of the guitar controller; FIG. 4 is a right side view of the guitar controller; FIG. 5 is a left side view of the guitar controller; FIG. 6 is a top view of the guitar controller; FIG. 7 is a bottom view of the guitar controller; FIG. 8 is a perspective view of the guitar controller positioned on a guitar; and, FIG. 9 is an alternative perspective view of the guitar controller positioned on a guitar. The broken lines are included for the purpose of illustrating portions of the guitar controller and form no part of the claimed design.

1 Claim, 8 Drawing Sheets(56)
